V. L. EMERSON

PROCESS FOR CONVERSION OF HYDROCARBON OILS AND SIMILAR SUBSTANCES

Filed Nov. 3, 1919

Patented Feb. 19, 1924.

1,484,014

UNITED STATES PATENT OFFICE.

VICTOR LEE EMERSON, OF PHILADELPHIA, PENNSYLVANIA.

PROCESS FOR CONVERSION OF HYDROCARBON OILS AND SIMILAR SUBSTANCES.

Application filed November 3, 1919. Serial No. 335,563.

To all whom it may concern:

Be it known that I, VICTOR LEE EMERSON, a citizen of the United States, residing at Philadelphia, Pennsylvania, have invented 5 certain new and useful Improvements in Processes for Conversion of Hydrocarbon Oils and Similar Substances, of which the following is a specification.

While this invention relates broadly to 10 the distillation and conversion of complex chemical combinations into new atomic groups, it relates more specifically to a process for the conversion of heavy hydrocarbons into a lighter product and to eliminate 15 largely the sulphur and water and other similar foreign compounds to prevent them from forming objectionable combinations in the still, such as carbon bisulphide, and to prevent the elements of oxygen and hydro- 20 gen contained in the water from forming explosive compounds by uniting with the hot carbonaceous vapors in the still. Oil stills have usually been fed directly with the oil before previously treating the same 25 with the result that hard carbon formations are formed in the stills, which it is difficult to remove, often resulting in the still burning out. Violent explosions have also taken place when there was apparently but little 30 pressure on the stills. These are apparently due to the result of a small quantity of water or moisture being pumped into the stills while they were at high temperature. Also sulphur accompanies the oil in many cases. 35 The oxygen of the water, combining with the carbonaceous gases, forms chemical combina- 40 tions in which combustion takes place rapidly supported by the hydrogen contained in the water and the sulphurous gases present, and violent explosions follow.

With the present method these dangers are entirely avoided, as the contained water and sulphur compounds are removed prior to the introduction of the heavy oil into the 45 still.

It is an object of the present invention to provide for the removal of foreign compounds from the heavy oil prior to the admission of the same into the still.

It is a further object of the present invention to utilize the heat in the gaseous products coming from the still to pre-heat the

oils before they are pumped into the still to evaporate any water held in suspension and to remove any sulphurous compounds that might enter into combination with either the oil or water or the gaseous products therefrom. At the same time a portion of the heavier products coming over in gaseous form from the still are condensed by contact 60 with the incoming supply of fresh oil which is at a lower temperature and conversely such readily volatilizable material in the incoming oils is transformed into gaseous form by the heat transmitted to the same 65 from the gaseous products which come in contact with the fresh oils.

It is likewise an object of this invention to subject the fresh supply of incoming oil to the action of the jets and the heat of the 70 gaseous products from the still and to combine the same with such products from the still as are condensed on contact with the fresh supply of oil. The preheated and pre-treated fresh oil and condensates are injected 75 into the material contained in the still and are subjected to a cracking reaction by reason of the fact that the injected materials have a lower boiling point and lower temperature than the material into which they 80 are injected. It is obvious that the material into which they are injected is at a com- 85 paratively higher boiling point and a com- paratively higher temperature than the material injected, this being due to the fact that the material in the still has been robbed of the oil of lower boiling points by distilla-

In carrying out my process the hydrocarbons having a relatively low boiling point 90 are subjected to the residual hydrocarbons undergoing treatment under relatively high pressure and temperature and which have a relatively high boiling point. The supply of the relatively low boiling hydrocarbons to 95 the relatively high boiling material in the still not only utilizes the temperature and heat of the high boiling hydrocarbons to cause a "cracking" reaction of the lower boil- 100 ing hydrocarbons, but the low boiling hydro- carbons, when intermixed with the high boiling hydrocarbons, act to maintain the entire mixture in such a state as to avoid the formation of hard carbon and free gas

by excessive cracking due to the extreme temperatures accompanying a reduction of the distillate to a very high boiling point with its attendant high temperature which is 5 present to a large extent in the well known processes.

It is a still further object to utilize the pressure and velocity of the gaseous products as they come from the still to produce 10 molecular dissociation by impact either of the gaseous products themselves or in combination with the heavy oil, the molecular dissociation by impact producing a condition inductive to the formation of new atomic 15 groups and aid the production of a product of lighter specific gravity.

It is a still further object to utilize the kinetic energy contained in the gaseous products as they come from the still to produce 20 an ionizing or similar effect that is inductive to the formation of new atomic groups.

Other objects and advantages of the invention will appear hereinafter. In my Patents Nos. 1,367,807, Feb. 8, 1921; 1,346,797, 25 July 13, 1920; 1,346,798, July 13, 1920; 1,414,400, May 2, 1922; granted upon co-pending applications and copending application Serial No. 380,171, filed May 10, 1920, all of which are continuations in part 30 of this application, I have claimed certain processes and apparatus which are disclosed in this application but not claimed herein.

In order to render my present invention clear, reference is had to the accompanying 35 drawings in which—

The figure is a vertical section of one form of my device as adapted for carrying out the conversion of petroleum.

In the apparatus disclosed in the drawings for carrying out the process of conversion, a receptacle 1 of any desired shape or size is provided to which the heavy hydro-carbon 2 is fed through a suitable feed pipe 3, which is controlled by a valve 4. This 40 valve may be either manually or automatically controlled to maintain a certain predetermined quantity of heavy fluid in the apparatus, the valve 4 as herein shown being controlled by a float 5 which is adjustable by 45 the thumb screw 6 seated in the top wall of the receptacle. The revolute member of the valve 4 is connected to the float 5 by means of a bar 5'. The float in its vertical movement controls the degree of oscillation 50 of the valve 4 and brings the opening in the periphery 4' of the latter into or out of register with the feed pipe 3 and the receptacle 1 for the purpose to be hereinafter described. The bottom of the receptacle 1 is preferably 55 tapered toward a central outlet 7 controlled by a gate valve or other closure means 8 through which the carbonaceous and other solid material may be drawn off from time to time. A suitable pedestal 9 is provided 60 for supporting the receptacle 1 at a con-

venient height to permit the valve 8 to be manipulated. In the lower portion of the wall of the receptacle an outlet pipe 10 is provided, through which outlet the contents of the receptacle, after treatment therein, may be pumped or forced to the still. It will thus be evident that the above apparatus forms an intermediary between the source of supply and the still. Within the apparatus the supply is purified, preheated and predistilled to a certain extent. It also follows that the fresh material will serve to condense such portions of the gaseous products passing through said material as are condensable at the temperature at which the material is maintained. These condensates along with the predistilled oil are now carried to the still through the pipe 10 and are injected into the material contained in the still which has a relatively higher boiling point and higher temperature.

The top wall of the receptacle 1 has a central opening with a downwardly depending member 11, which member terminates in a vertical pipe 12, the lower end of which carries a flaring or bell-shaped member 13. This bell-shaped member extends to points adjacent the wall of the receptacle 1 and is there perforated with a series of holes 14. Surrounding the member 11 and concentric therewith is a tubular baffle member 25 for the purpose of promoting circulation within the receptacle.

Diametrically disposed in the top wall of the receptacle 1 are mounted vertical pipes 15 terminating at their lower portion and below the flanged member 13 in elbows 16, the inner ends of the elbows being open and providing free entry for the fluid contained in the receptacle into the pipe 15. The upper ends of the pipes 15 are connected through regulating valves 17 with the chambered cross pipes 18. The pipes 18 terminate radially of the receptacle 1 in jet nozzles 19 having a common axis through the diameter of the receptacle 1. A reaction chamber 20, which is mounted upon the top wall of the receptacle 1, and in continuation of the pipe 11, is adapted to surround the jets 19.

Entrant jets 21 form part of the cross member 18 and terminate above the axis of the pipes 15. The entrant jets are fed from a manifold 22 which is adapted for connection to the still by means of pipe 24 and a regulating valve 23 to control the supply of gaseous products therefrom. While only two jets or nozzles are shown in the present modification, it is of course to be understood that any number of jets, together with their accompanying pipes 15, may be employed, or a single jet may play on a baffle.

Mounted on the top wall of the receptacle 1 is a dome 26 which is provided with a supply outlet pipe 27 to lead the volatile

products to a condenser or other suitable apparatus for receiving and separating the products of the process according to their volatility or power of absorption.

5 In carrying out the present process, valve 23 is opened permitting the gaseous products under relatively high pressure from the still or boiler to pass through the manifold 22 into the jets or nozzles 21. While my 10 process is capable of being carried out through a wide range of temperatures and pressures and the details of the apparatus are capable of variation within the scope of my invention, which is not limited to the 15 particular temperatures, pressures or details mentioned, the following is given as an example of the execution of my process in a particular instance. I find that satisfactory results will be obtained by the use of a pressure 20 in the still of one hundred pounds per square inch with an accompanying temperature of seven hundred to eight hundred degrees F. In order to impart the proper kinetic energy to the gaseous products at such a 25 temperature and pressure satisfactory results may be obtained by the use of a jet apparatus following a design based upon the standard practice in connection with steam injectors for the feed water of boilers. By 30 regulating the oil supplied to the jets the liquid in the base 1 can be maintained at a point which will condense those portions of the products of impact which it is desirable to subject to further dissociation and allow 35 the gaseous products to pass off which compose the final product. The fluid or vapors from the still pass through these jets which impinge upon each other in the reaction chamber 20. The jets are so designed as to 40 give the gases issuing therefrom a very high velocity and the kinetic energy imparted to the gaseous products, is expended at the point of impact of the jets.

It is of course unnecessary to go into an 45 extended discussion of the reactions that take place at the point of impact of the jets. While not limiting myself to any one theory or hypothesis, it would appear that the high 50 velocity of the gaseous products gives rise to a molecular attrition of extreme violence at the point of impact and a large amount of heat is liberated at this point, the development and liberation of heat at the point of 55 impact of the gaseous streams acting to dissociate the molecules. The preheating of the hydrocarbon mass causes the hydrocarbons to approach the point of impact under relatively high temperature and consequent readiness to split up or, as it is technically known, "be cracked" by the action of 60 impact. This dissociation is further aided by the shock of impact and the attendant phenomena of attrition which not only gives rise to heat by friction, but promotes the reduction of the mass into its constituent 65 molecules.

The dissociation of the molecules with the attendant atomic rearrangements gives rise to new and simpler atomic groups. In obtaining this dissociation by impact and its attendant phenomena, there is an absence of the surrounding pressure which would otherwise be essential were it to be carried out in a confined chamber under heat. Thus, the molecular dissociation of high boiling hydrocarbons is accomplished 70 which, in the ordinary processes, would require a heat productive of the pressure which would be destructive to the containing vessel. Due to the expenditure of kinetic energy it also appears probable that an 75 electrical charge is present with its consequent ionizing effect. It is sufficient to say that due apparently to some such effects as these, a molecular re-arrangement is produced and new atomic groups are formed, 80 a very large proportion of the lighter and simpler hydrocarbons resulting from this reaction.

The gaseous products from this step now 85 pass down the pipe 11 and bubble up 90 through the body of liquid 2 in the receptacle 1. In this way the heat brought over by the stream of volatile material from the still and the heat caused by the impact of the jets, serves to heat the body of liquid as a 95 preliminary step to its treatment in the still. By this means the temperature of the receptacle and its contents is kept well above the boiling point of water and the water contained in the heavy oil is thereby 100 entrained as vapor by the gaseous products and carried out through the vapor dome 26, together with the sulphur vapors and sulphurous compounds. By this action the 105 heavy oil is dehydrated and desulphurized prior to its treatment in the still, and the lighter hydrocarbons already existing in the heavy oil are fractionally removed before they enter the still. It may also be possible 110 that some additional action may take place between the freely ionized gaseous products from the jets and the heavy material in the receptacle.

The use of the baffle member 25 serves 115 to set up convection currents which materially aid in the heating of the material and the separation of solid material from the oil before treatment in the still. The upwardly moving material carries the 120 gaseous products in bubbles which, released at the surface of the fluid, permits the latter to return through the channel between the pipe 12 and the member 25. The solid material settles to the bottom of the receptacle 1 and is drawn off periodically by means of the valve 8.

125 While the reaction just discussed may be carried out without the presence of liquid material, it may become advantageous under certain circumstances to inject into 130

- 15 the reaction chamber and in the field of the impinging jets a certain proportion of the crude oil. By suitable manipulation of the valves 17 the nozzles 19 and 21 constitute injectors which serve to lift the liquid through the pipes 15, mix it with the incoming jets of hot gaseous products from the still, and project the mixture at high velocity into the reaction chamber 20
- 5 10 where it is subjected to treatment by heat and impact. In actual operation it is desirable to operate the valve 17 so as to regulate the flow of oil to the jets in such a manner that in the preliminary steps to 15 operation a sufficient flow of oil may be passed through the jets to quickly heat up the oil to the desired point. The flow of oil is then diminished to such a point that the gaseous products may impart a high 20 velocity to the same in a very finely divided state. Thereafter they are subjected to impact with its consequent reaction. In this manner the breaking down of the higher hydrocarbons from the still is promoted, and the water vapor present in the 25 oil may enter into the reaction taking place at the jets, a hydrogenating effect taking place. If desired, water could be added to the heavy oil in the receptacle 30 or directly to the jets in order to increase the hydrogenating effect. Hydrogen gas could also be admitted in the same manner and for the same purpose. By passing the oil directly through the jets a large portion 35 of the heavy oil undergoes treatment and lighter hydrocarbons are formed therefrom without the necessity of subjecting the entire body of heavy oil to treatment in the still. In connection with 40 Figure 1 I have shown a conventional form of still and indicated the connections between it and the apparatus therein disclosed. As will be seen, the preheated and pretreated fluid in receptacle 1 is supplied 45 to the still by a pump to which the pipe 10 is connected. The heated gaseous products under pressure from the still are indicated as being supplied to the pipe 24.
- In the cycle of operations followed in 50 carrying out my method the still supplies hydrocarbon gaseous products under pressure and heat to the jets 19 where the gaseous products are treated by impact. The heavy hydrocarbon oils are also treated 55 by impact repeatedly since they pass up through the pipe 15 into the influence of the jets. Such portion of the products of this treatment of heavy hydrocarbon oil by impact and the products of the treatment 60 of the gaseous products from the still by impact as are not removed in the gaseous state through the pipe 27 are supplied to the still, thus completing the cycle of operations.
- 65 The products of distillation which come

over from the still include true gases, such as hydrogen, vapors, saturated vapors and gases and particles of the material undergoing distillation which remain in the liquid form and are held in suspension by 70 the gaseous products. I have used the term "gaseous products" to cover all the material coming over from the still as described.

The term "attrition" has been used in 75 the description of the reaction taken place between the impinging jets, but it should be understood that this term not only covers a mechanical attrition but a molecular and atomic attrition as well in the 80 present instance.

It will be apparent that the gaseous products and liquid hydrocarbons are rapidly subjected to temperature changes. 85 The gaseous products on reaching the jets have been cooled by expansion, thereafter they are heated by impact and are again cooled by being brought in contact with the liquids in the receptacle which are maintained at a lower temperature than 90 the gases. The liquids in the receptacle are raised in temperature by intermixture with the gaseous products from the still and undergo the temperature changes along with these gaseous products. This constant rapid change of temperature promotes dissociation of the hydrocarbon molecules by subjecting them to repeated and sudden changes in stress due to the temperature changes which tend to overcome 95 their chemical inertia.

While the particular embodiment of my invention has been described with reference to the treatment of petroleum for the production of lighter hydrocarbons, it is of course to be understood that the same process is equally applicable to chemical compounds other than hydrocarbons.

It is also to be understood that other 100 conditions and reactions than those described may be present in the process and within the scope of the invention as defined in the appended claims.

What I claim is:—

1. The process of conversion of hydrocarbon oils which consists in imparting sufficient kinetic energy to a mass of the same to cause dissociation on impact, subjecting said energized mass to impact, repeatedly subjecting the resultant products to impact together with a portion of fresh hydrocarbon oil, subjecting the products of impact thus formed to intimate contact with the hydrocarbon oil and drawing off 115 the gaseous products.

2. The process of conversion of hydrocarbon oils which consists in imparting sufficient kinetic energy to a mass of the same to cause dissociation on impact, subjecting said energized mass to impact by the 120

125

130

mutual impingement of jets of the same, formed to intimate contact with a fresh subjecting the resultant products to impact, imparting kinetic energy to a separate mass of hydrocarbon oil by mixing the same with said first mentioned energized mass, subjecting the mixture to impact, subjecting the products of impact thus

10

In testimony whereof I have hereunto set my hand.

VICTOR LEE EMERSON.
